UNITED STATES PATENT OFFICE.

OSCAR STANKEY AND MARTIN CHRIST, OF EAST ST. LOUIS, ILLINOIS.

SAFETY-INDICATOR FOR RAILWAYS.

No. 882,802.

Specification of Letters Patent. Patented March 24, 1908.

Application filed April 17, 1907. Serial No. 223,776.

To all whom it may concern:

Be it known that we, OSCAR STANKEY and MARTIN CHRIST, both citizens of the United States, and residents of East St. Louis, Illinois, have invented certain new and useful Improvements in Safety-Indicators for Railways, of which the following is a specification, containing a full, clear, and exact description, reference being had to the accompanying drawings, forming a part hereof:

Our invention relates to a safety indicator for railways, our object being to provide a simple, compact appliance to be located in the apartment occupied by the engineer or driver of a train or car, which appliance serves to continuously remind the engineer or driver of a station or stopping point where a second train or car is to be met; and which arrangement is intended to prevent wrecks due to engineers and drivers disregarding signals or orders relative to the meeting of trains at certain points.

To the above purposes, our invention consists in certain novel features of construction and arrangement of parts, which will be hereinafter more fully set forth; pointed out in the claims, and illustrated in the accompanying drawings, in which:

Figure 1 is a front elevation of our appliance, with the front wall thereof removed; Fig. 2 is a vertical section taken on the line 2—2 of Fig. 1; Fig. 3 is a horizontal section taken on the line 3—3 of Fig. 1; Fig. 4 is a horizontal section taken on the line 4—4 of Fig. 1.

Referring by numerals to the accompanying drawings:—1 designates the frame, or body, of our improved appliance, which is in the form of a rectangular box, in the front wall of which is located a section of glass 2, or analogous transparent material, and the rear wall of the box being provided with a door 3, on the inner face of which is removably held a reflector 4.

Vertically arranged within the box is a partition 5, which divides said box into two compartments; and formed in said partition is a plurality of horizontally disposed slots 6, there being three of these slots shown in the present construction.

Arranged for rotation in bearings, such as 7, located in the side walls of the box, at the upper and lower ends of the compartment in front of the partition 5, are the shafts 8, the

left hand ends of which extend beyond the side wall of the box, and are provided with small hand wheels 9, by means of which said shafts are rotated. (See Fig. 1.) The opposite ends of these shafts which extend beyond the opposite side of the box are threaded, and receive lock nuts 10. Positioned on each shaft, within the box and adjacent the end on which the hand wheels 9 are mounted is a roller 11, and operating thereupon is a belt 12, thus providing means for the simultaneous rotation of said shafts.

Located upon the shafts 8, and arranged to wind from one to the other, is a sheet 13, of flexible material, such as paper or cloth; and formed therein, by perforations 14, are the letters forming the names of the stations along the line on which the apparatus is used; and formed immediately opposite the names of the stations, adjacent the side edges of the sheet 13, are rectangular apertures 15.

A roller 16 is journaled for rotation between each roller 8 and the partition 5, and the sheet 13 passes behind these rollers 16, thus holding the exposed portion of the sheet 13 immediately adjacent the transverse openings 6 in the partition 5.

Located on the rear side of the partition 5, immediately above and below the openings 6 therein, are keepers 17, in which are formed the pairs of oppositely arranged grooves 18; and fitted in the pair of grooves of each pair of keepers 17, immediately adjacent the openings 6, are sections of colored glass 19. One of these sections of glass 19 is preferably green, another red, and the remaining one white, which colors are intended to indicate different trains; for instance, a "regular," a "special," or a "freight." Arranged to slide through openings 20 formed in one of the side walls of the box and to engage in the rear pairs of grooves 18 are non-transparent plates 21, which, when in position, cut off the light to the sections of colored glass 19.

Arranged within the compartment to the rear of the partition 5, and immediately in front of the reflector 4, is a lamp 22.

Fixed on the side of the frame 1 is a circular disk 23, on which is arranged a clock face, and through which passes a shaft 24 carrying the usual clock hands, and which shaft is rotated by a knob 25, thus providing an indicator which may be turned and adjusted to

indicate any particular time desired, for instance, the time at which the train on which the apparatus is located is due at a certain station, the name of which latter is displayed 5 by the station indicator.

The use of our improved indicator is as follows: Assuming that the appliance is positioned in the cab of a locomotive, and that the engineer has orders to meet a regular 10 train at a certain station, the lock nuts 10 are loosened to allow the shafts 8 to be freely rotated, and one of the hand wheels 9 is now engaged and manipulated so as to roll the sheet 13 from one shaft 8 to the other until 15 the name of the station designated as a meeting point is brought into a position immediately in front of the opening 6, which is covered by the section of red glass. The slides 21 are inserted in the grooves of the keepers 20 behind the sections of green and white glass, thus covering said sections, and light from the lamp 22 is thrown forward by the reflector 4 through the section of red glass 19; and in turn appears through the perforations 25 forming the letters of the name of the station designated, and also through the openings 15 adjacent the name of the station. After the sheet 13 has been shifted to the proper position, the lock nuts 10 are tightened to hold 30 the shafts 8 against any rotation, thus preventing any shifting of the sheet 13 due to vibration of the locomotive or car upon which the appliance is carried. Thus the appliance is set for use, and the engineer or driver of the 35 locomotive or car is constantly reminded of the particular station where a "regular" train is to be met. By shifting the slides 21, the section of green or white glass may be exposed, as desired, to indicate "special" and 40 "freight" trains; and, if desired, a greater number of openings, such as 6, may be employed to meet various conditions.

An appliance of our improved construction is simple, inexpensive, easily adjusted and 45 set for use, serves as a constant reminder as to the designated meeting points for trains, and the like, and, when properly used, greatly reduces the liability of accidents resulting from disregarding orders and instructions.

We claim:—

1. In a device of the class described, a 50 housing, a partition arranged therein, in which partition is formed a series of openings, sections of colored glass arranged immediately to the rear of said openings, a perforated sheet arranged for operation so as to pass in front of all of the openings in the partition, a lamp arranged in the housing to the rear of the partition, and non-transparent plates arranged to slide in the housing immediately to 55 the rear of the sections of colored glass.

2. In a device of the class described, a 60 housing in the front wall of which is formed a glazed opening, a partition within the housing in which partition is formed a series of 65 openings, sections of colored glass arranged over said openings, non-transparent plates adapted to be positioned over the sections of colored glass, a lamp arranged within the housing to the rear of the partition, a pair of 70 rollers operated in the housing in front of the partition, a perforated flexible sheet arranged to wind upon the rollers, and means whereby both rollers are simultaneously rotated.

3. In a device of the class described, a 75 housing in the front wall of which is formed a glazed opening, a partition within the housing in which partition is formed a series of 80 openings, sections of colored glass arranged over said openings, non-transparent plates 85 adapted to be positioned over the sections of colored glass, a lamp arranged within the housing to the rear of the partition, a pair of rollers operated in the housing in front of the partition, a perforated flexible sheet arranged to wind upon the rollers, means whereby both rollers are simultaneously rotated, and means whereby said rollers are locked against rotation.

In testimony whereof we have signed our 90 names to this specification, in presence of two subscribing witnesses.

OSCAR STANKEY.
MARTIN CHRIST.
